UNITED STATES PATENT OFFICE

138,228

DESIGN FOR A TOY ERECTOR BLOCK

Eoina Nudelman, Chicago, Ill.

Application April 24, 1944, Serial No. 113,350

Term of patent 7 years

(Cl. D34—15)

To all whom it may concern:

Be it known that I, Eoina Nudelman, a citizen of France, residing at Chicago, in the county of Cook and State of Illinois, have invented a new, original, and ornamental Design for Toy Erector Blocks, of which the following is a specification, reference being had to the accompanying drawing, forming part thereof,

Fig. 1 is a front elevational view of a toy erector block, showing my new design; and

Fig. 2 is a side view of the same.

I claim:

The ornamental design for a toy erector block, as shown,

EOINA NUDELMAN,
